GRINDING OR HONING MACHINE

John William Howlett, Lymington, England, assignor of one-half to Wellworthy Piston Rings Limited, Lymington, England, a British company

Application August 6, 1951, Serial No. 240,543

Claims priority, application Great Britain
August 23, 1950

11 Claims. (Cl. 51—112)

1
The present invention relates to a machine for grinding or honing the side walls of split piston rings and has for an object to provide a machine in which the split rings are fed between abrading wheels with the gap in the ring trailing to lessen the possibility of damage to the horns defining the gap.

The present invention consists in a machine for grinding or honing the side walls of split piston rings, in which a pair of grinding or honing wheels are arranged horizontally, that is with their axes vertically, one above the other with a gap therebetween through which the rings are continuously fed to grind or hone both side walls simultaneously, guide means being provided for guiding the rings between the wheels substantially diametrically thereacross, and wherein the rings are fed edgewise into the gap between the wheels by feeding means which advance them along a horizontal table, the rings to be machined being stored in a magazine having means adapted to engage with the gaps in the rings to orientate them in a direction such that the rings successively removed from the magazine by the feeding means will be fed to the gap between the wheels with the gaps in the rings at the trailing side of the ring.

The magazine may be adjustable to accommodate different sizes of rings, and preferably comprises a V-member and a T-shaped member, both arranged vertically above the feed table, the V-shaped member being to the forward side of the ring (with reference to the direction in which it is advanced towards the wheels) and the T-shaped member at the trailing side of the ring, the web of the T being such that it can fit within and locate the ring gaps. The V-shaped member and the T-member may be adjustable towards and away from one another for adjustment for different sizes of rings.

The rings in the magazine are successively withdrawn from the base of the magazine through an opening at the base of the V-member of a depth greater than the width of a single ring, but less than the width of two rings, by means of a feed belt rotatable along the surface of the feed table. The rings are thus fed into a channel to a pair of driven feed rollers, having resilient surfaces which are pressed together to grip a ring by its side walls, these feed rollers positively advancing the rings in succession through a further channel which leads to the gap between the cutting wheels which rotate in opposite directions.

The surface of the feed table may form the bottom wall of the channel which may be closed at its top by removable members which may be spaced at different distances from the surface of the feed table to accommodate different widths of ring. The side walls of the feed channel are pref-

erably formed by two guide strips of less thickness than the width to which the rings are to be ground or honed, which strips extend along the surface of the feed table, between the cutting wheels, and over the surface of a table at the other side of the wheel on to which the machined rings are ejected. This pair of guide strips are preferably made of metal and each may be mounted on stud bolts or other means at its two extreme ends, the distance between the pair of stud bolts (one for each strip) at each end of the machine being adjustable to vary the spacing between the strips. This adjustment may be effected by the bolts being carried on brackets or the like mounted on a lead screw with right and left-hand portions co-operating with the brackets respectively. After the lead screws have been turned to adjust the brackets to the correct spacing, the strips may be tensioned by tightening further bolts acting longitudinally of the strips and then locking them in the adjusted position.

The feed table is made adjustable in height so that its surface may be adjusted to lie exactly level with the surface of the lower cutting wheel. The surface of the outlet table may be similarly adjustable in the vertical direction.

Vertical adjustment of the feed table may be effected manually, for example, by a rotatable handle geared to raise or lower a pillar carrying the table. The motor for driving the feed rolls is preferably carried by the pillar by which the table is supported so that vertical adjustment of the pillar simultaneously raises or lowers the motor. Means may be provided for locking the pillar in the adjusted position.

The two cutting wheels are also mounted so as to be adjustable vertically with respect to one another for setting the machine for grinding or honing the rings to the desired width.

2
In order that the invention may be clearly understood, an embodiment thereof will now be described by way of example with reference to the accompanying drawings. In the drawings:

Fig. 1 is a side elevation, partly in section, of a machine according to the invention.

Fig. 2 is an end view of the machine viewed from the left of Fig. 1.

Fig. 3 is a plan view of the magazine, and

Figs. 4, 5, 6, 7, 8 and 9 are sectional views along the lines IV—IV, V—V, VI—VI, VII—VII, VIII—VIII and IX—IX respectively of Fig. 1.

Referring to the drawings, 1 is the base of the machine upon which is mounted a pedestal 2 for the feed table 3 and a support 4 for the cutting wheels 5 and 6 carried on vertical driving spindles 7 and 8 respectively. The latter are rotated in opposite directions by electric motors 9 and 10 respectively through belt drives 11 and 12 respectively.

Vertically mounted on the feed table 3 is a

magazine comprising a V-shaped member 13 and T-shaped member 14 for holding a stack of rings to be ground. As indicated in Fig. 3 the V-shaped member 13 is to the forward side of the ring 15 with reference to the direction in which the ring is fed towards the cutting wheels and the T-shaped member 14 is at the trailing side of the ring with the web portion 16 fitting within the gap 17 of the ring to accurately locate the ring for feeding towards the cutting wheels with the ring gap at the trailing side of the ring. The T-shaped member 14 is carried on an angle bracket 18 (Figs. 1, 3 and 4) clamped to a bridge member 19 by bolt 20 passing through a slot 21 in the angle bracket and engaging in a threaded bore 22 in the bridge member 19. The latter spans the feed table 3 and is secured thereto by screws 23. By slackening the bolt 20 the T-shaped member 14 can be adjusted towards and away from the V-shaped member 13 to accommodate different sizes of rings.

The V-shaped member 13 is secured to a supporting bridge member 24 by bolt 25 passing through a slot 26 in the bridge member to permit vertical adjustment of the V-shaped member 13 by means of the adjusting screw 27 threaded through a lug 28 on the member 13 and abutting against a face 29 on the bridge member 24. The gap 30 between the bottom of member 13 and the plane of the top surface of the feed table 3 can thus be adjusted for rings of different thicknesses to permit the passage of the lowermost ring from the stack, the gap being adjusted to a value greater than the thickness of one ring but less than the thickness of two rings.

The feeding forward of the rings 15 is effected by means of an endless belt 31 mounted on driving pulleys 32 and 33 carried on shafts 34 and 35 respectively carried in bearings in the side walls of supporting structures 36 and 37 respectively for the feed table 3, which structures are carried on a platform 38 on a tubular support 39 slidable vertically within the pedestal 2. The tubular member 39 carries an electric motor 40 for driving the endless conveyor belt 31, the drive being taken by V belts from the pulley 41 on the motor shaft 42 to a worm box 43 at the rear of pedestal 2. A pulley 44 on the output shaft of the worm box drives a pulley 46 on shaft 34 by means of V belts 47.

The rings 15 are fed by the belt 31 along the table 3 to a pair of feed rollers 48, 49 (Figs. 1 and 6) of which at least the top one has a resilient surface 45, the rollers being pressed together to grip a ring by its side walls, so that the rollers positively advance the rings in succession to the cutting wheels. The lowermost feed roller 49 is driven by chain 50 from a sprocket 51 on the shaft 34, the chain driving a sprocket 52 on the spindle 53 carrying roller 49. A second sprocket 54 on shaft 34 drives by chain 55 a sprocket 56 on a lay shaft 57 (Figs. 1 and 7) carried in a support 58 on the top of the feed table 3. Lay shaft 57 has a gear 59 keyed thereto meshing with the pinion 60 on spindle 61 carrying the upper feed roller 48, the pinion being fixed to the roller by pins 62 and 63. The feed rollers are thus driven to push the rings positively towards the honing wheels.

After being ground or honed between the wheels 5 and 6 the rings are received on to an outlet table 64 adjustably mounted, as herein-after described, on the end wall of support member 4. The rings are guided through the machine by guide channels extending between the

various components. These guide channels are constituted by two guide strips 65 and 66 of less thickness than that to which the rings are to be ground or honed, which strips extend along the surface of the feed table 3, between the cutting wheels 5 and 6, and over the surface of the outlet table 64. This pair of guide strips is preferably made of metal and each strip is mounted on bolts at opposite extreme ends of the machine. At the right hand end of the machine, as viewed in Fig. 1, the strips are secured to brackets 67 (Figs. 1 and 8) by nut and bolt connections 68. The brackets are carried on stud bolts 69 having securing nuts 70 and carried on a lead screw 71 extending transversely of the machine and having threaded portions 72 and 73 of opposite hand co-operating with the stud bolts 69. The lead screw 71 is provided with a knurled wheel 74 by which it may be rotated to adjust the distance between the brackets 67 and hence the strips 65 and 66 to adjust the distance between the brackets 67 and hence the strips 65 and 66 to adjust the spacing of the guide strips according to the diameter of the rings to be fed through the machine. The strips 65 and 66 are similarly mounted at the left hand end of the machine, as viewed in Fig. 1, on bolts 75 and 76 respectively (Fig. 9) mounted on a lead screw 77 having threaded portions 78 and 79 of opposite hand, and an adjusting wheel 80. After the lead screws have been turned to adjust the strips to the correct spacing, the strips are tensioned by tightening bolts 81 carried on the brackets 67 at the right hand end of feed table 3, as viewed in Fig. 1, and acting longitudinally of the strips against the end of the table.

The bottoms of the feed channels are formed by the surface of the outlet table 64 and of the feed table 3 and the tops of the channels are formed by removable members 84, 85 and 86 carried in bridge members 81, 88 and 89 respectively and vertically adjustable therein by means of threaded connecting rods projecting through the tops of the bridge members and fitted with adjusting hand nuts 90, 91 and 92 respectively and locking nuts 93, 94 and 95 respectively.

The feed table 3 is made adjustable in height so that its surface may be adjusted to lie exactly level with the surface of the lower cutting wheel 6. To this end the tubular member 39 (Fig. 1) carrying the feed table is provided with an internal flange 96 resting on a flange 97 of a ring nut 98 threaded internally at 99 to engage a threaded pillar 100 carried on the base of the machine. The ring nut 97 is rotated, to raise or lower member 39, by means of a bevel wheel 101 secured to the ring nut by bolts 102 and meshing with a bevel wheel 103 keyed to the inner end of a shaft 104 the outer end of which projects through an opening 105 in the pedestal 2 and is provided with flats 106 for receiving a turning handle.

It will be seen from Fig. 1 that the motor 40 for driving the feed rolls and the conveyor belt is mounted on the table-supporting member 39 so that vertical adjustment of the table simultaneously raises or lowers the motor. A threaded bolt 107 having a rotating handle 108 is carried in a threaded bore in the pedestal 2 and acts against a resilient block 109 for locking the member 39 in the adjusted position.

The outlet table 64 is also vertically adjustable so that it can be brought to lie level with the surface of the lower cutting wheel 6. To this end the table 64 is supported on a bracket 110

secured to the end wall of support 4 by means of bolts 111 and 112 carried in the wall and extending through vertical slots 113 and 114 respectively in the bracket 110. An adjusting bolt 115 having a turning handle 116 is carried in a bracket member 117 on member 4 and engages bracket 110 to effect vertical adjustment thereof when the nuts 111 and 112 have been slackened. These nuts are tightened after adjustment of the table.

The upper cutting wheel 5 is vertically adjustable relative to the lower cutting wheel 6 for setting the machine for grinding or honing the rings to the desired width. To this end a vertical rack 118 on the upper wheel assembly is engaged by a pinion 119 rotated by a worm drive 120, 121 from a hand wheel 122.

Whilst a particular embodiment has been described, it will be understood that various modifications may be made, without departing from the scope of the invention.

I claim:

1. A machine for abrading the side walls of split piston rings comprising a feed table, a magazine thereon for the rings to be machined, a pair of horizontal abrading wheels rotatably mounted one above the other about vertical axes and with a gap therebetween at the level of the feed table, means operatively connected to said abrading wheels to rotate said wheels in opposite directions, conveyor means for the rings mounted for movement along said feed table from said magazine towards said abrading wheels and arranged to remove the rings successively from said magazine and feed them along said feed table to the gap between said abrading wheels, driving means operatively connected to said conveyor means, and guide means extending between said abrading wheels to guide the rings between said wheels substantially diametrically thereacross whereby both sides of the rings are abraded simultaneously, said magazine comprising a V-shaped member and a T-shaped member both arranged vertically above the feed table, said V-shaped member being on the side nearer said abrading wheels, and said T-shaped member being on the side more remote therefrom and the web of the T being such that it can fit within and locate the ring gaps.

2. A machine as claimed in claim 1 wherein the V-shaped member and the T-shaped member are relatively adjustable to accommodate different sizes of rings.

3. A machine for abrading the side walls of split piston rings comprising a feed table, a magazine thereon for the rings to be machined, a pair of horizontal abrading wheels rotatably mounted one above the other about vertical axes and with a gap therebetween at the level of the feed table, means operatively connected to said abrading wheels to rotate said wheels in opposite directions, a feed belt mounted for movement along the surface of the table from said magazine towards said abrading wheels, driving means operatively connected to said feed belt, and guide means extending between said abrading wheels to guide the rings between the wheels substantially diametrically thereacross whereby both sides of the rings are abraded simultaneously, said magazine comprising a V-shaped member and a T-shaped member both arranged vertically above the feed table, said V-shaped member being to the side nearer said abrading wheels and having its lower end spaced from said feed table by a distance greater than the width

of a single ring but less than the width of two rings, whereby the rings are successively withdrawn from the base of the magazine by means of said feed belt, and said T-shaped member being at the side remote from said abrading wheels, the web of the T being such that it can fit within and locate the ring gaps.

4. A machine for abrading the side walls of split piston rings comprising a feed table, a magazine thereon for the rings to be machined, a pair of horizontal abrading wheels rotatably mounted one above the other about vertical axes and with a gap therebetween at the level of the feed table, means operatively connected to said abrading wheels to rotate said wheels in opposite directions, a feed belt mounted for movement along the surface of the table from said magazine towards said abrading wheels, driving means operatively connected to said feed belt, and guide means extending between said abrading wheels to guide the rings between the wheels substantially diametrically thereacross whereby both sides of the ring are abraded simultaneously, said magazine comprising a V-shaped member and a T-shaped member both arranged vertically above the feed table, a supporting member on the feed table for the V-shaped member, adjustable securing means securing said V-shaped member to said supporting member for vertical adjustment relative thereto and to the feed belt, said V-shaped member being to the side nearer said abrading wheels, a supporting member on said feed table for said T-shaped member, adjustable securing means securing said supporting means, to said feed table for horizontal adjustment towards and away from said V-shaped member, said T-shaped member being at the side remote from said abrading wheels, and the web of the T being such that it can fit within and locate the ring gaps.

5. A machine for abrading the side walls of split piston rings comprising a feed table, a magazine thereon for the rings to be machined, a pair of horizontal abrading wheels rotatably mounted one above the other about vertical axes and with a gap therebetween at the level of the feed table, means operatively connected to said abrading wheels to rotate said wheels in opposite directions, a feed belt mounted for movement along the surface of the table from said magazine towards said abrading wheels, driving means operatively connected to said feed belt, a pair of feed rollers rotatably mounted between said feed belt and said abrading wheels and arranged to engage the rings as they leave the feed belt, at least one of said rollers having a resilient surface, means acting on said rollers to press them together, and means operatively connected to said rollers for rotating the rollers to feed the rings towards the abrading wheels, guide means for the rings extending at least from said feed rollers through the gap between said abrading wheels to guide the ring between said abrading wheels substantially diametrically thereacross whereby both sides of the rings are abraded simultaneously, said magazine including guide means on the side remote from said abrading wheels and adapted to engage with the gaps in the split rings to orientate them with the gap therein remote from said abrading wheels, whereby the rings successively removed from the magazine are fed towards the abrading wheels with the gaps in the rings at the trailing side of the ring.

6. A machine for abrading the side walls of split piston rings comprising a feed table, a magazine thereon for the rings to be machined, a pair

of horizontal abrading wheels rotatably mounted one above the other about vertical axes and with a gap therebetween at the level of the feed table, means operatively connected to said abrading wheels to rotate said wheels in opposite directions, a feed belt mounted for movement along the surface of the table from said magazine towards said abrading wheels, driving means operatively connected to said feed belt, a pair of feed rollers rotatably mounted between said feed belt and said abrading wheels and arranged to engage the rings as they leave the feed belt, at least one of said rollers having a resilient surface, means acting on said rollers to press them together, and means operatively connected to said rollers for rotating the rollers to feed the rings towards the abrading wheels, guide means for the ring extending at least from said feed rollers through the gap between said abrading wheels to guide the ring between said abrading wheels substantially diametrically thereacross whereby both sides of the rings are abraded simultaneously, said magazine comprising a V-shaped member and a T-shaped member both arranged vertically above the feed table, said V-shaped member being nearer said abrading wheels, and said T-shaped member being more remote therefrom and the web of the T being such that it can fit within and locate the ring gaps.

7. A machine for abrading the side walls of split piston rings comprising a feed table, a magazine thereon for the rings to be machined, a pair of horizontal abrading wheels rotatably mounted one above the other about vertical axes and with a gap therebetween at the level of the feed table, means operatively connected to said abrading wheels to rotate said wheels in opposite directions, a feed belt mounted for movement along the surface of the table from said magazine towards said abrading wheels, driving means operatively connected to said feed belt, a pair of feed rollers rotatably mounted between said feed belt and said abrading wheels and arranged to engage the rings as they leave the feed belt, at least one of said rollers having a resilient surface, means acting on said rollers to press them together, and means operatively connected to said rollers for rotating the rollers to feed the rings towards the abrading wheels, guide means for guiding the rings from said feed rollers to the gap between said abrading wheels and through said gap diametrically across said abrading wheels, said guide means comprising a pair of strips of less thickness than the width to which the rings are to be machined and extending along the feed table from one end thereof to the other and between said abrading wheels, and removable members covering said strips between said magazine and said feed rollers and between said feed rollers and said abrading wheels, said magazine comprising a V-shaped member and a T-shaped member both arranged vertically above the feed table, said V-shaped member being nearer said abrading wheels, and said T-shaped member being more remote therefrom and the web of the T being such that it can fit within and locate the ring gaps.

8. In a machine as claimed in claim 7, a transverse lead screw at each end of the feed table, each lead screw having two threaded portions of opposite hand, and a pair of strip supporting members, one supporting member for each strip, mounted on the threaded portions of each lead

7 screw, whereby the spacing of the strips can be adjusted by rotating the lead screw.

9. In a machine as claimed in claim 7, a transverse lead screw adjacent an end of the feed table, said lead screw having two threaded portions of opposite hand, and a pair of strip supporting members, one supporting member for each strip, each supporting member comprising a stud bolt and a bracket carrying said bolt, said stud bolt being mounted on the lead screw, means at one end of each bracket connecting said bracket to the corresponding strip and a bolt at the other end of each bracket threaded through a threaded bore therein longitudinally of the feed table and engaging the end wall of said feed table whereby said strips can be tensioned by tightening said bolts.

10. In a machine as claimed in claim 7 vertically adjustable means supporting said removable cover members for the guide strips whereby said cover members are vertically adjustable to accommodate rings of different widths.

11. A machine for abrading the side walls of split piston rings comprising a feed table, an externally screw threaded pillar, a ring nut on said screw threaded pillar, a horizontal external flange on said ring nut, a tubular shank depending from said feed table and carried by said flange on said ring nut to support said table, and means operatively connected to said ring nut to rotate said ring nut to raise or lower said table, a magazine on said feed table for the rings to be machined, a pair of horizontal abrading wheels rotatably mounted one above the other about vertical axes and with a gap therebetween at the level of the feed table, means operatively connected to said abrading wheels to rotate said wheels in opposite directions, conveyor means for the rings, mounted for movement along said feed table from said magazine towards said abrading wheels and arranged to remove the rings successively from said magazine and feed them along said feed table to the gap between said abrading wheels, driving means operatively connected to said conveyor means and guide means extending between said abrading wheels to guide the rings between said wheels substantially diametrically thereacross whereby both sides of the rings are abraded simultaneously, said magazine including guide means on the side remote from said abrading wheels and adapted to engage with the gaps in the split rings to orientate them with the gap therein remote from said abrading wheels whereby the rings successively removed from said magazine are fed towards said abrading wheels with the gaps in the rings at the trailing side of the ring.
